UNITED STATES PATENT OFFICE.

RUDOLPH J. J. MUELLER, OF SHEBOYGAN, WISCONSIN, ASSIGNOR TO UNIVERSAL OXYGEN COMPANY, OF SHEBOYGAN, WISCONSIN, A CORPORATION OF WISCONSIN.

CHEESE-HOOP.

1,255,629.

Specification of Letters Patent.

Patented Feb. 5, 1918.

Application filed April 15, 1915. Serial No. 21,600.

To all whom it may concern:

Be it known that I, RUDOLPH J. J. MUELLER, a citizen of the United States, residing at Sheboygan, in the county of Sheboygan and State of Wisconsin, have invented certain new and useful Improvements in Cheese-Hoops, of which the following is a specification, reference being had to the accompanying drawing, forming a part thereof.

10 The main objects of this invention are to produce sanitary sheet metal cheese hoops without riveted or lapped joints forming crevices in which dirt can lodge; to facilitate drainage of the whey from the curd 15 while it is subjected to pressure in such hoops; to facilitate cleansing the hoops; to hold the bandage cloth securely in place in the hoops during the preliminary pressing operation without cutting or mutilating the 20 same; and generally to improve the construction and operation of metal cheese hoops.

It consists in the construction, arrangement and combination of parts as hereinabove particularly described and pointed out in the claims.

In the accompanying drawing like characters designate the same parts in the several figures.

30 Figure 1 is an axial section in a plane indicated by the line 1—1, Fig. 2, of a complete metal cheese hoop embodying the invention, and a part of another like hoop inserted therein; Fig. 2 is a cross section on the line 2—2, Fig. 1; Fig. 3 is a similar section on the line 3—3, Fig. 1; and Fig. 4 is a partial section of the follower on the line 4—4, Fig. 2.

The hoop, which is made of heavy sheet 40 metal, comprises a tapering body section *a*, formed at its larger end with an outturned flange *b*, a cylindrical top section *c*, butt welded at one end to the top of the flange *b* next to its periphery, and a perforated bottom section *e*, butt welded inside the body section at its smaller end. The flange *b*, which is primarily made of a little larger diameter than the top section *c*, so as to project slightly beyond its outer face, is fused over the adjoining edge of the top section *c*, to strengthen

and insure closing the joint between them. In like manner the bottom edge of the body section is made to project slightly below the lower face of the bottom section *e*, and is fused inwardly over the joint between them, 55 as shown in Fig. 1. Both sections *a* and *c* are made from flat pieces of sheet metal, opposite edges of which are brought together in shaping them to the desired form and are butt welded in longitudinal seams *d*, thus 60 avoiding lapped joints and crevices in which dirt can lodge, and producing continuous unbroken surfaces both inside and outside of the hoop, which can be easily kept clean and in a perfectly sanitary condition. 65

The body section *a*, is provided with an external bearing ring or shoulder *f*, and on opposite sides with metal handles *g*, which are welded thereto so as to avoid crevices in which dirt can lodge.

70 The hoop is provided with the usual elastic split bandage holding sleeve *h*, which is removably fitted in the top section *c* and adapted to bear at its inner end against the internal shoulder formed by the flange *b* at 75 the junction of the body and top sections, as shown in Fig. 1. This sleeve is made somewhat wider or of greater depth than the top section *c*, so as to project therefrom when its inner end bears against said shoulder. It is 80 made flaring at its outer end, as shown in Fig. 1, to facilitate the insertion of the follower as hereinafter explained.

The hoop is also provided with a one-piece follower *i*, preferably made of aluminium 85 or other non-corrosive metal. It is formed with an upturned marginal flange and a peripheral groove in which a packing ring *j*, of rubber or other suitable elastic material, is fitted and held to form a tight joint between the follower and the sleeve *h*, through which it is guided into the upper or larger end of the body section *a*, in the operation of the hoop. On its upper or outer side the follower is formed at intervals with bosses 90 *k* and *k'*, which by engagement with the press plunger or bottom of an adjoining hoop provides a drainage space through which whey expressed from the curd can 95 freely escape around the margin of the 100

follower into the space between the sleeve *h* and the plunger or smaller end of a hoop serving as a plunger, as shown in Fig. 1. The bosses *k'*, which are spaced around the 5 follower next to its periphery, are formed with undercut holes, as shown in Figs. 2 and 4, in which sharp or flat pointed hooks may be inserted without mutilating or injuring the cheese, for withdrawing the follower 10 from the hoop after the pressing of the cheese is completed.

The upturned marginal flange of the follower presents a broad face to the interior surface of the bandage sleeve and hoop and 15 tends to prevent the tilting of the follower in the hoop and also tends to prevent the squeezing of the curd or cheese upwardly or outwardly between the margin of the follower and the bandage sleeve or hoop, besides stiffening and strengthening the follower and admitting of its being made comparatively thin and light.

The under or inner face of the follower being made plain or smooth, without protuberances, avoids mutilating or disfiguring 25 the cheese.

In practice, hoops of this kind, when filled 30 with curd, are usually arranged end to end in a horizontal or inclined position in a gang press, the smaller end of each hoop except the last in the series, being inserted in the larger end of an adjoining hoop through the flaring end of the bandage holding sleeve *h*, and bearing against a follower *i*, 35 as shown in Fig. 1.

For preliminary pressing, the bandage cloth is placed around the sleeve *h*, which is then inserted with the cloth on the outer side thereof, in the hoop, as shown in Fig. 1, 40 the cloth extending into the tapering body section *a*, from the inner end of the sleeve. The hoop is then filled with curd to or nearly to the top of the sleeve *h*, and a follower *i* placed thereon. After the follower 45 has been thrust from the sleeve *h* into the body section *a* of the hoop and the greater part of the whey has been expressed from the curd, the press plunger is withdrawn, the hoops are separated, the sleeves *h* and 50 the followers *i* are removed, and the bandage cloths are folded inwardly over the exposed ends of the cheeses around which they are wrapped. The sleeves *h* are then replaced 55 in the hoops, the followers *i* are inserted therein, and the hoops being assembled as before, the cheeses are subjected to a final pressing operation.

To afford free drainage for the whey 60 from the curd and cheese during the above mentioned pressing operations, the drainage holes *m* in the bottom section *e*, are arranged in groups adjacent to its periphery, as shown in Fig. 3, and the drainage holes *n* in the follower are distributed over its

whole area, some of them close to its margin, 65 so that whatever side of the hoop may be placed downward in the press, the whey will find a free exit from the lower side of the hoop at both ends.

The top of the flange *b* forms a sharp or 70 abrupt angle with the inner face of the top section *c*, thus enabling the sleeve *h* when inserted with a bandage cloth in the hoop to securely bind and hold the cloth in place 75 therein. The corner at the inner edge of the shoulder formed by the flange *b* being rounded, avoids cutting, tearing or mutilating the bandage cloth, which passes inwardly over it from the outer side of the sleeve *h* into the tapering body section *a* of 80 the hoop.

Various changes in minor details of construction and arrangement of parts may be made within the scope of the invention as defined in the following claims. 85

I claim:

1. A sheet metal cheese hoop comprising a tapering body portion and a separately formed cylindrical top section, the body portion being formed at its larger end with an outwardly turned flange to which the lower edge of the cylindrical section is fused to make a tight joint and leave an internal shoulder to receive the lower edge of a bandage holding sleeve between which and said shoulder the bandage will be gripped. 95

2. A sheet metal cheese hoop comprising a tapering body portion and a separately formed cylindrical top section, the body portion being formed at its larger end with an outwardly turned flange having a rounded edge at its junction with the inner face of the body portion, and the lower edge of the cylindrical top section being fused to the flange to make a tight joint and leave an internal shoulder to receive the edge of a bandage holding sleeve. 105

3. A sheet metal cheese hoop comprising a body section having a bottom and an outwardly flange at its upper end, a top section 110 butt-welded at one end to said flange and forming therewith an internal shoulder at the junction of the sections, a split sheet metal bandage holding sleeve removably fitted into the top section against said shoulder and of the same thickness as the width of the shoulder, and a one-piece perforated metal follower fitting into said sleeve and the upper part of the body section of the hoop and formed with an upturned marginal flange presenting an extended face to the interior of the sleeve and hoop, said follower being formed at intervals on the upper side with bosses and having a plain, smooth under face. 115

4. A metal cheese hoop comprising a tapering body section having a perforated bottom at its smaller end, a cylindrical top 120

section attached to the larger end of the body section, an inwardly projecting shoulder being formed at the junction of the top and body sections, a split bandage holding 5 sleeve removably fitted into said top section against said shoulder, and a perforated follower formed at intervals on the upper side with perforated undercut bosses and having a grooved periphery provided with a pack-

ing ring which fits snugly within said sleeve 10 and the larger end of the body section.

In witness whereof I hereto affix my signature in presence of two witnesses.

RUDOLPH J. J. MUELLER.
